UNITED STATES PATENT OFFICE

170,844

TRAFFIC BAR

Grant A. Wiswell, Burlingame, Calif.

Application May 25, 1953, Serial No. 25,175

Term of patent 14 years

(Cl. D72—1)

To all whom it may concern:

Be it known that I, Grant A. Wiswell, a citizen of the United States of America, residing at Burlingame, county of San Mateo, State of California, have invented a new, original, and ornamental Design for Traffic Bar, of which the following is a specification, reference being had to the accompanying drawings forming a part hereof:

Fig. 1 is a perspective view of a traffic bar, showing my new design.

Fig. 2 is a top plan view.

Fig. 3 is a side elevational view.

Fig. 4 is a bottom plan view.

Fig. 5 is an end elevational view of one end of the traffic bar.

Fig. 6 is an end elevational view of the opposite end of the traffic bar.

I claim:

The ornamental design for a traffic bar, as shown.

GRANT A. WISWELL.
